UNITED STATES PATENT OFFICE.

HENRY R. GRIFFEN, OF PHOENIXVILLE, PENNSYLVANIA.

APPARATUS FOR PLAYING DUPLICATE WHIST.

SPECIFICATION forming part of Letters Patent No. 619,404, dated February 14, 1899.

Application filed December 23, 1897. Serial No. 663,178. (No model.)

To all whom it may concern:

Be it known that I, HENRY R. GRIFFEN, a citizen of the United States, residing at Phoenixville, in the county of Chester and State 5 of Pennsylvania, have invented certain new and useful Improvements for Apparatus for Playing Duplicate Whist, of which the following is a specification.

As is well known, in playing duplicate whist, 10 a series of packs of cards are employed, each pack being divided or dealt to form four hands; after the original play with a pack the hands are kept separate from each other; and in the duplicate play each pair of players is provided with the hands which were 15 held by their opponents in the original series of games.

The keeping of the hands of a considerable 20 number of packs of cards in this separated condition,—the disposition of the hands and packs in such mechanical carriers as will permit them in the duplicate play to be as to the individual packs selected at random, so that the series of individual games shall not in the 25 duplicate play be used in the same sequence as in the original,—and, the employment of indicators as to which of the players shall “lead” as the several packs are played in the duplicate series in irregular order,—have 30 heretofore involved the use of carrying and distributing apparatus of a somewhat cumbersome and unsatisfactory character.

It is the object of my invention to provide 35 a table beneath the surface board of which, within a box-like top, are disposed a series of carrier pockets in which the individual hands of the large number of packs of cards may be distributed in a selected sequence, said carrier pockets being movable with respect to 40 the table top, and adapted to be shifted to successive positions, in which they register with openings in said table,—in combination with means whereby the hands contained in 45 pockets which register with such openings, may be ejected through them,—locking mechanism being provided to secure the carrier pockets in fixed positions until the hands thus ejected are after being played returned to them through the slots.

50 My invention further comprehends a novel system and arrangement of devices to indi-

cate the successive leads and deals, and devices to keep the scores of the successive plays.

My invention further comprehends certain 55 details of mounting, construction and arrangement, all as hereinafter more fully and at large set forth.

In the accompanying drawings I show and herein I describe a good form of a convenient 60 embodiment of my invention, the particular subject-matter claimed as novel being hereinafter definitely specified.

In the drawings,

Figure 1 is a top plan view of a casing constituting the table top, and in which the working parts of my apparatus are contained.

Figure 2 is a view in end elevation of the same.

Figure 3 is a top plan view of the apparatus, 70 the lid of the box or casing being shown as raised to exhibit the contained parts.

Figure 4 is a vertical, sectional, elevation of the apparatus shown in Figure 3, section being supposed in the plane of the dotted line 75 4 of Figure 3, and sight being taken in the direction of the arrows applied to said line.

Figure 5 is a top plan view of a box or casing with the lid raised, the card carrier being supposed removed to exhibit the parts ordinarily 80 mounted beneath it.

Figure 6 is a vertical, sectional, elevation, of the devices shown in Figure 5, section being taken on the dotted line 66 of said figure, and sight being taken in the direction of the arrows applied to said line.

Figure 7 is a vertical, sectional, elevation of the parts shown in Figure 3, section being supposed on the dotted line 77 of said figure, and sight being taken in the direction of the 90 arrows applied to said line.

Figure 8 is a view in perspective of the plunger frame.

Figure 9 is a view in elevation of the shaft locking apparatus.

Similar letters of reference indicate corresponding parts.

In the drawings,

A is a casing or box-like structure conveniently constituting a table top, having a bottom and side walls permanently united, and removable or hinged lid α , in which are formed

four card slots $a' a^2 a^3 a^4$,—four indicator openings $b' b^2 b^3 b^4$ and a record sheet opening a^x , all as shown particularly in Figure 1.

The four card slots are shown as disposed 5 in such arrangement that each exists in proximity to one of the sides of the table; thus the slot a^2 is near the north side, the slot a^4 near the east side, the slot a^3 near the south side, and the slot a' near the west side, so that the 10 players located respectively at the four sides of the table, take their cards from and return them through the nearest slot.

Within the hollow interior of the box or casing is disposed a movable card carrier, C, consisting, in the embodiment of my invention 15 illustrated, of a structure equipped with four tiers of pockets, which tiers are arranged in parallelism, the arrangement being such that each tier of pockets, in the movement of the 20 carrier, is carried along beneath a particular card slot in the table top, the tier c^2 being always beneath the card slot a^2 , the tier c^4 being always beneath the card slot a^4 , the tier c' being always beneath the card slot a' , and the 25 tier c^3 being always beneath the card slot a^3 .

The pockets of the four tiers are assumed to be numbered consecutively from the left hand ends of the tiers to the right hand ends, and the tiers while in parallelism, are out of 30 lateral alinement, that is, are placed in such staggered relationship, as shown fully in Figure 3, that pockets bearing a common ordinal will always contemporaneously present respectively beneath the four card slots, thus, 35 for instance, when the third pocket of the tier c^2 is beneath the card slot a^2 , the third pocket of the tier c^4 will be beneath the card slot a^4 , the third pocket of the tier c' beneath the card slot a' , and the third pocket of the 40 tier c^3 beneath the card slot a^3 .

The packs of cards as they are "dealt" and divided into four "hands," are to be inserted in pockets of the four tiers bearing a common ordinal, and this may be done either by lifting the lid a before the playing begins and placing said hands in the particular pockets in the manner stated, or the hands may be dealt at the time they are played originally and immediately after each original play with 45 a pack, the four "hands" may be inserted by the four players, each player inserting the hand held by him through the card slot nearest to him, with the result of course that owing to the arrangement of the card carrier the four 50 "hands" will descend into pockets beneath said slots bearing identical ordinals.

In playing the "hands" originally, after each hand is played, it may be placed in the pockets of the card carrier,—the rack being 55 moved at random in alternate directions beneath said slots,—with the result that if the cards are in the duplicate play selected, first, from the first pockets at the left hand end of the carrier, played and returned, next from the second pocket at the left hand end of the carrier, played and returned, next from the third pocket, played and returned, and so on,

the packs will not, in said duplicate play, be used in the same order in which they were used in the original.

As will be understood, the staggered arrangement of the card carrier rack is made necessary by the disposition shown of the card slots, and, as is obvious, if the card slots $a' a^2$ should be formed in the table top at points 75 farther to the left, the distance between the left hand ends of the tiers $c' c^2$ from the left hand ends of tiers $c^3 c^4$ would be correspondingly increased, while on the other hand should said card slots $a' a^2$ be formed farther 80 to the right hand or "east" side of said table the left hand ends of said tiers $c' c^2$ would be brought to a position more closely adjacent to the left hand ends of the tiers $c^3 c^4$.

The traveling card carrier is formed of a series of four trough-like receptacles, $d' d^2 d^3 d^4$, firmly united to each other in parallelism, and each divided by a series of transverse partitions c^x into a series or tier of card pockets, the carrier, as a whole, resting and traveling 90 upon rails d^x extending from the east.

An opening or slot d^l is formed in the bottom of each of the trough-like receptacles $d' d^2 d^3 d^4$ and extends from end to end of the same, and recesses or openings of width corresponding 95 to said slots are formed in the lower ends of each of the transverse partitions c^x .

Each of the trough-like receptacles is provided at one of its upper edges with a ledge or plate, designated respectively $e' e^2 e^3 e^4$ 100 which register beneath the indicator openings $b' b^2 b^3 b^4$ and upon said ledges are inscribed the words "Lead" and "Deal," the arrangement being such that as each series of pockets present beneath the card slots in the manner stated the word "Deal" inscribed on one of said ledges will appear at one of the indicator openings and the word "Lead" inscribed on another of said ledges will appear beneath another of said indicator openings, the distribution of the words "Deal" and "Lead" 105 upon the ledges being such that they will present beneath these openings in a systematic manner, that is to say, in the use of the card carrier and in its progress from end to end of the box or casing, in which it will stop with its pockets in registry with the card slots twenty-four times, the word "Lead" will appear six times, and the word "Deal" will appear six times, beneath each of the indicator 110 openings, the word "Lead" always appearing beneath one opening, the word "Deal" contemporaneously appearing beneath another opening, and blank spaces of the ledges 115 contemporaneously appearing beneath the two other openings, with the result that in the play of the twenty-four packs each player is to be considered as "dealer" for six times and as "leader" six times.

In Figure 3 the word "Deal" is supposed 120 to be imprinted on the ledges wherever an asterisk appears, and the word "Lead" wherever a small dash appears.

F is a record sheet holder, moving with, and,

preferably as shown, formed as a part of or connected to, the card-carrier, said record sheet holder being a plate of any desired character provided with an inturned edge or flange 5 f (Figures 3 and 4) or other devices to secure the record sheets or similar devices upon its upper surface, said sheets being of the character shown in Figure 3.

This sheet is divided into five longitudinal 10 spaces, at the left hand end of which are respectively inscribed "Hand number," "Original," "Duplicate," "Original gain," "Duplicate gain."

Said longitudinal spaces divided by a series 15 of transverse lines each into twenty-four squares.

In the first series of squares opposite the words "Hand number," are placed the numerals 1, 2, 3, 4, etc.

20 The record sheet opening a^x in the table top is a narrow slot of length and breadth approximating the space between two of the transverse lines of the record sheet, and in said opening are arranged mounted free for 25 sliding movement two small blocks f^x .

When the first card pockets at the left hand ends of the tiers of card pockets present beneath the card slots the transverse space designated "1" of the record sheet will present 30 beneath the record sheet opening, and throughout the movement of the card carrier, that transverse space of the record sheet the number of which corresponds to the card pockets beneath the card slots will present beneath the record sheet opening.

35 On the record sheet is kept the score of the players at the north and south sides or of those at the east and west sides as the case may be, it being, of course, unnecessary to 40 keep the score of both the north and south and the east and west sides.

In the original play, as soon as a hand has been played the number of tricks made by the north and south hands is set down in the 45 transverse space presented beneath the record sheet opening, opposite the word "Original."

In said original play one of the sliding blocks f^x may be moved to the upper end of 50 the record sheet opening and when in that position it will conceal the numbers on the upper edge of the record sheet, so that the players will not know the numbers of the hands they are playing.

55 In the duplicate play the second sliding block f^x is moved to the upper end of the record sheet opening and against the first of the said blocks already, as stated, in that position, and in that position said second sliding block conceals the entries made of the "tricks" taken in the original play.

Some players desire, as soon as a hand is played in the duplicate, to compare the result with the result reached in the original 65 play,—and in my apparatus this comparison may very readily be made as the score of the original play is exposed,—without exposing

the scores of any of the other original plays—by simply sliding the second of the blocks f^x to the lower portion of the record sheet opening. 70

In said duplicate play the tricks made by the north and south hands are set down in the transverse spaces opposite the word "Duplicate."

If in the duplicate play the card carrier be 75 shifted to and fro, and the hands played somewhat at random as to successive order, the players will not fall into the error of twice playing in said duplicate play the same hands, because, as soon as a hand has been played, 80 and its result set down opposite to the word "Duplicate," said result will always be visible beneath the score card opening whenever those hands present beneath the card slots, and thereby the players are made aware that 85 the hands so presenting are hands which have already been played by them in the duplicate play.

d^5 is a stop block mounted on one of the rails d^x and provided with a set screw, said 90 block being adapted to be moved to and secured in different positions of adjustment on said rail.

When it is desired to play ten, twelve, fourteen, or other number of hands less than the 95 whole number of twenty-four said block is moved to an appropriate position on said rail, and secured in such position, with the result that the card carrier can only move a certain distance to the left, that is sufficiently far to 100 carry for example its first ten, twelve, or fourteen, card pockets beneath the card slots.

Any desired means may be employed to occasion the propulsion of the card carrier.

In practice I prefer to provide devices of 105 the character shown in the drawings.

In the drawings, g , Figure 7, is a rack secured to the under face of the card carrier and g' is a gear mounted on a shaft g^3 engaged in suitable bearings and extending to the exterior of the box or casing where it is provided with a knob g^3 adapted to be manually rotated and reciprocated.

The rack is of width in excess of that of the gear wheel so that said wheel with its shaft 115 may be moved longitudinally without disengaging from said rack.

g^x , Figure 9, is an escutcheon plate, through the center of which said shaft g^2 extends, mounted upon the inner wall of the box or 120 casing and provided with a series of openings g^6 arranged in a circumferential series about its center,—and g^4 is a bolt carrier mounted upon the shaft g^2 and provided with a bolt which in the rotation of said shaft registers 125 with said openings g^6 .

When the knob and shaft are forced inwardly, said bolt is carried out of the opening in which it happens to be engaged, and in the rotation of said knob the gear wheel, 130 through the rack, imparts movement to the card carrier until the latter is brought to a selected position.

As soon as this occurs, the bolt, in the out-

ward movement of the shaft and knob, engages in one of the openings g^6 , and the shaft and gear wheel, and consequently the card carrier become temporarily locked in position.

5 Preferably the shaft g^3 is forced outward through the agency of a spiral spring g^5 coiled upon it and operating against a part of the framework of the casing upon the one hand and against the gear wheel itself on the other.

10 A recess in the wall of the box or casing allows of the movement in or out of the knob g^3 .

In the use of the apparatus, when the card carrier has been brought to a position in which the desired card pockets are in registry with 15 the card slots, the cards contained in said pockets are to be forced upward through said card slots, and mechanism for this purpose and of a neat and workman-like character is shown in the accompanying drawings.

20 It is what I term a plunger frame, the same consisting of a device carrying four plungers $h' h^2 h^3 h^4$, disposed beneath and respectively in registry with the four card slots referred to, and adapted, upon the elevation of the 25 frame, to pass through the slots in the bottoms of the respective troughs, and within the four card pockets above them, to elevate the cards contained in said pockets through the card slots.

30 The plungers are preferably made as shown of slightly greater diameter than the depth from front to back of the individual card pockets, so that they are rendered absolute in their action of elevating the cards in the card pockets, this excess of the diameter of the plungers being made possible by the presence of the slots or openings in the partitions which 35 form the card pockets.

The plunger-frame itself, consists merely of 40 two parallel bars h , which exist in openings in the bottom of the box or casing, and are connected at their respective ends through transverse bars or plates h^x as shown, each of said transverse bars or plates being provided 45 with outwardly-extending projections, designated $i' i^2 i^3 i^4$.

J is a rock shaft journaled in suitable bearings within the box or casing, and protruding as to one end beyond the box or casing, said 50 protruding end being provided with an operating knob, J^x .

Within the box or casing said shaft is provided with a pair of arms $j j$ rigidly affixed to it, one of which extends beneath the projection i^2 , and the other beneath the projection i^4 .

55 K is a shaft mounted within the box or casing, in parallelism with the shaft J, and upon which are rigidly mounted a pair of arms k , which extend beneath the projections 60 $i' i^3$ respectively.

Manifestly, when rotation to the right, in unison, is imparted to the shafts J K, the arms $j k$ attached to said shafts will occasion the elevation of the plunger frame.

65 Rotation is to be imparted to the shaft J through the knob J^x on its outer end, and I prefer to transmit such rotation to the shaft K

through the devices shown in Figure 4, which consist of a pair of vertical arms $j^2 k^2$ respectively mounted upon said respective shafts 70 and connected as to their upper extremities by a link j^3 .

Having thus described my invention, I claim and desire to secure by Letters Patent—

75 1. In combination with a table top embodying card slots, indicator openings, and a record sheet opening, a card carrier equipped with a series of card pockets arranged in parallel tiers, indicating marks or words mounted 80 on said card carrier, and presenting beneath the indicator openings, a record sheet carried by said card carrier and presenting beneath the record sheet opening, and means for occasioning the movement of said card 85 carrier, substantially as set forth.

2. In combination with a table top embodying card slots and indicator openings, arranged in staggered relationship, and a record sheet opening, a card carrier disposed 90 and arranged to travel beneath said top, and embodying parallel tiers of card pockets, said tiers being out of lateral alinement, and indicators and a record sheet carried by said card carrier, substantially as set forth. 95

3. A table top embodying card slots, and a record sheet opening, a card carrier embodying card pockets, arranged to move beneath said table top and to come to rest with the card pockets in register by sets with said 100 card slots, a record carrying plate disposed beneath said table top, and moving beneath said opening in unison with the card carrier, substantially as set forth.

4. A table top embodying card slots and a record sheet opening, a card carrier embodying card pockets, arranged to move beneath said table top and to come to rest with the card pockets in register by sets with said 110 card slots, a record carrying plate disposed beneath said table top, and moving beneath said record sheet opening in unison with the movement of the card carrier, and means for closing part of said record sheet opening to shut from view entries previously made on the 115 record sheet, substantially as set forth.

5. The combination, to form an apparatus for playing duplicate whist, of a box or casing, the top of said box or casing embodying four card slots, and a record sheet opening, 120 a card carrier mounted within said top or casing and comprising four tiers of card pockets arranged in parallelism, a record sheet carried by said card carrier, and means for occasioning the movement of said card carrier 125 beneath the top of said casing, the arrangement being such, that in whatever position said carrier comes to rest, four card pockets will be in registry with the four card slots respectively, said card pockets being at corresponding distances from the ends of the tiers in which they are respectively located, substantially as set forth.

6. The combination to form an apparatus

- for playing duplicate whist, of a box or casing, the top of said box or casing embodying four card slots, a card carrier mounted within said top or casing and comprising four tiers 5 of card pockets arranged in parallelism, the arrangement being such that in whatever position said carrier comes to rest, four card pockets will be in registry with the four card slots respectively, said card pockets being at 10 corresponding distances from the ends of the tiers in which they are respectively located, a rack, secured to said card carrier, and a shaft provided with a gear wheel engaged with said rack, and provided with an operating knob, substantially as set forth.
7. The combination to form an apparatus for playing duplicate whist, of a box or casing, the top of said box or casing embodying four card slots, and four indicator openings, 20 a movable card carrier mounted within said top or casing and comprising four tiers of card pockets arranged in parallelism, and a series of indicators mounted on said carrier in the vicinity of each tier of pockets, the arrangement being such, that in whatever position said carrier comes to rest, four card pockets will be in registry with the four card slots respectively, and indicators will be in registry with indicator openings, said card 25 pockets being at corresponding distances from the ends of the tiers in which they are respectively located, a rack, secured to said card carrier, and a shaft provided with a gear wheel engaged with said rack, and with an operating knob, said shaft being capable of longitudinal movement, a bolt carried by said shaft, and a series of openings in which said bolt engages when forced outward, substantially as set forth.
- 30 8. The combination to form an apparatus for playing duplicate whist of a box or casing, the top of said box or casing embodying four card slots, and four indicator openings, a movable card carrier mounted within said top or casing and comprising four tiers of card pockets arranged in parallelism, and a series of indicators mounted on said carrier in the vicinity of each tier of pockets, the arrangement being such, that in whatever position 35 said carrier comes to rest, four card pockets will be in registry with the four card slots respectively, and indicators will be in registry with indicator openings, said card pockets being at corresponding distances from the ends of the tiers in which they are respectively located, a rack, secured to said card carrier, a shaft provided with a gear wheel engaged with said rack, and also provided with an operating knob, said shaft being capable of longitudinal movement, a bolt carried by said shaft, and a series of openings in which said bolt engages when forced outward, and a spring adapted to force said shaft outward, substantially as set forth.
- 40 9. The combination to form an apparatus for playing duplicate whist, of a table top or casing, a card carrier embodying a series of card pockets arranged in parallelism, and each provided with a series of partitions to form a series of card pockets, 45 openings in the table top with which said pockets register, slots formed in the bottom of said trough-like structures, a series of plungers in registry with said openings in the top, and of breadth slightly in excess of the depth 50 from front to back of the individual card pockets, said plungers being mounted upon a frame equipped four projecting ends, a rock shaft, provided with arms which extend beneath two of said ends, a second rock-shaft 55 provided with arms, which extend beneath the other two of said projecting ends, a knob mounted on the first mentioned of said shaft, and mechanism for imparting rotation from said first mentioned shaft to the second, substantially as set forth.
10. A combination to form an apparatus for playing duplicate whist, of a table top or casing, a card carrier embodying a series of trough-like receptacles, firmly united in parallelism, and each provided with a series of partitions to form a series of card pockets, 60 openings in the table top with which said pockets register, slots formed in the bottom of said trough-like structures, a series of plungers in registry with said openings in the top, and of breadth slightly in excess of the depth 65 from front to back of the individual card pockets, said plungers being mounted upon a frame equipped with four projecting ends, a rock-shaft, provided with arms which extend beneath two of said ends, a second rock-shaft 70 provided with arms, which extend beneath the other two of said projecting ends, a knob mounted on the first mentioned of said shaft, and mechanism for imparting rotation from said first mentioned shaft to the second, substantially as set forth.
11. In an apparatus for playing duplicate whist, a top or casing, embodying a series of apertures, a card carrier embodying a series of card pockets, arranged to move in unison 75 beneath said openings, and a device for limiting the movement of said card carrier, so that only a selected number of said pockets shall be moved beneath said slots, substantially as set forth.
12. In an apparatus for playing duplicate whist, a top or casing, embodying a record sheet opening, a plurality of blocks arranged for sliding movement in said opening, and means for supporting and moving a record 80 sheet beneath said opening, substantially as set forth.

In testimony that I claim the foregoing as my invention I have hereunto signed my name this 11th day of December, A. D. 1897.

HENRY R. GRIFFEN.

In presence of—

C. S. YARNALL,
IRVIN S. YARNALL.
